UNITED STATES PATENT OFFICE

2,519,008

PRINTING DISK WITH DETACHABLE TYPE

Joseph Weimont, Bogota, N. J., assignor to A. Kimball Company, New York, N. Y., a corporation of New York

Application June 17, 1944, Serial No. 540,783

4 Claims. (Cl. 101—377)

1

The present invention relates to a printing device, and more particularly to a printing device especially adapted for use in marking machines.

In the present type of marking machines now in use for printing price tags, pin tickets and the like, it is customary to use a type chase wherein the type is changed for each new run of tags or tickets. In cases where it may be desirable to print a thousand or more tickets with identical indicia, such type changing is not a serious burden. But where, as is more often the case, it is desired to print a short run of say ten to one hundred tickets with one setting, and then another short run with another setting, it is obvious that much time will be lost in resetting type for each run of tickets to be printed.

It is an object of the invention to provide a printing device wherein a plurality of relatively thin disks carrying a set of type are placed face to face on a shaft so that the type at the portion of the disks presented to the ticket to be printed are close together, so that a large number of characters may be printed on very small tickets.

Another object of the invention is the provision of means for quickly and easily adjusting the type carrying disks to bring the desired type characters to printing position.

Another object of the invention is the provision of novel means of removably holding the type in said disks so that worn out type may be readily replaced.

Other objects and advantages of the present invention will appear hereinafter.

A preferred embodiment of the invention selected for purposes of illustration is shown in the accompanying drawings, in which:

Figure 1 is a front view of the present invention, with parts broken away.

Figure 2 is a longitudinal section taken on the line 2—2 of Figure 3.

Figure 3 is a section on the line 3—3 of Figure 1.

Figure 4 is a detail of one of the disks with the end plate broken away to show how the type is mounted in the periphery thereof.

Figure 5 is a fragmentary view in perspective of the disks showing the type holding spring.

Figure 6 is a fragmentary detail in cross section through some of the disks showing them in a position where one piece of type may be removed, and

Figure 7 is a view similar to Figure 6 showing a piece of type being removed.

Referring to the drawings, the device comprises a series of concentric type carrying disks arranged in face to face relation, here shown eight in number, and referred to by the reference characters 11, 12, 13, 14, 15, 16, 17 and 18. Each of the type carrying disks 11 to 18 is secured to

2

one of a series of concentric or telescopic bushings 11' to 18', respectively, the four right hand disks being secured to bushings which extend to the right, and the four left hand disks being secured to bushings which extend to the left.

All of the type carrying disks 11 to 18 and their respective telescopic bushings 11' to 18' are rotatably mounted on a stationary shaft 19 which may be mounted on the frame of the marking machine frame in any suitable manner.

Each of the bushings 11' to 18' carries a pinion 11" to 18" which may be formed integrally therewith, as shown, or may be secured thereto in any suitable manner. Said pinions 11" to 18" mesh with gears 11''' to 18''' mounted on a second stationary shaft 20 running parallel to the shaft 19 and mounted on the frame of the machine in any suitable manner.

Each of the gears 11''' to 18''' carries a segment 21, rigidly secured thereto by small brackets 22, and each of said segments is marked with a series of indicia corresponding to and arranged in the same order as the characters of the type carried by the respective disks. Each of the segments 21, in turn is provided with an ear 23 by means of which the segments and gears may be manipulated as hereinafter described. A plate 24 may also be attached to any convenient part of the frame 25 of the machine, which said plate extends across the segments 21 and is provided with a series of windows 26 registering with the indicia on the segments, each of said windows being of a size to expose a single character of said indicia to the operator. The position of the segments and the position of the windows in the plate are adjusted, of course, so that the character on any segment which is exposed through its respective window corresponds to the face of the piece of type which is in printing position.

It will be observed that the pieces of type 27 are equally spaced around the periphery of the disks 11 to 18, the size of the disks being such as to permit carrying the number of type required for printing purposes with adequate spacing between type. The size of the pinions is so chosen as to permit all of the type carried by any disk to be brought to printing position with a limited motion of its corresponding segment 21. From the foregoing, it will be seen that the operator, before beginning a run of tickets, has merely to adjust the segments by manipulation of the ears 23 to expose the desired characters of a single line of type through the series of windows 26. When the segments are so adjusted, the corresponding pieces of type will be in printing position to cooperate with the platen P. The platen may be fixed, in which case the entire printing head assembly may be reciprocated for printing but I prefer to keep the printing head

55

50

60

stationary and to reciprocate the platen as indicated in Figure 3. The type may be inked in any suitable manner, but I prefer to use an ink ribbon (not shown) which may be fed between the printing head and the platen in any suitable manner.

In the ordinary operation of the disks the friction between adjacent disks and their respective bushings, as held on the shaft 19 by the collars 31 and 32, is sufficient to retain them in any position in which they may be set. However, if desired, suitable spring detents may be provided for this purpose.

In spite of the fact that the above described arrangement permits selective setting of the disks to bring any desired combination of type to printing position, so that the type may be set merely by rotating the disks as described, it is nevertheless important to permit individual pieces of type to be changed quickly and easily whenever necessary, as when a piece of type is broken or when certain pieces which are used more frequently than others become worn.

Referring to Figures 4, 5, 6 and 7, it will be seen that each piece of type 21 is carried in a radial groove 28 formed in one face of the disk, each groove having an undercut shoulder 29 to cooperate with the shoulder 29' on the type piece to hold the type firmly against longitudinal movement in the groove. Since the disks are arranged face to face, the type in each disk is held against sidewise motion by the abutting face of the next adjacent disk, except in the case of the disk 18, in which case the type is held by the thin non-type carrying disk 30.

Each of the disks 12 to 18 is provided with a single groove 33 terminating in a slot 34 extending clear through the entire thickness of the disk near the periphery thereof. A flat spring 35 is held in the groove 33 by a rivet 36 with the free end of the spring projecting into the slot 34 and bearing against the face of the next adjacent disk. Thus as the disks are rotated relative to one another in ordinary use the springs 35 prevent the pieces of type from falling out of the grooves 28 as they pass the slots 34. However, whenever it is desired to remove and replace a certain piece of type in a certain disk, it is only necessary to rotate the next adjacent disk until its slot 34 is opposite the groove 28 carrying the piece to be replaced as shown in Figures 5, 6 and 7. Then by tilting the piece of type as shown in Figure 7, it may be easily removed and a new piece inserted in its place.

From the foregoing it will be seen that it is not necessary to provide a slot 34 in the disk 11, since the type carried by disk 11 will be removed and inserted through slot 34 in disk 12. With respect to the disk 18, however, the same result may be accomplished by slitting the disk 39 to provide a peripheral slot 37 ordinarily closed by spring finger 38 which ordinarily holds the type in place, but may be bent outwardly to permit type to be removed from and inserted in the disk 18.

The portion of each of the disks where the slot 34 is formed may be used, of course, as a blank in places where no printing is desired.

It will be understood that the invention may be variously modified and embodied within the scope of the subjoined claims.

I claim as my invention:

1. A printing device comprising, a series of concentric type carrying disks arranged in face to face relation, each of said disks having type

carrying grooves in one face thereof, type in said grooves, the type in the grooves of one disk being held in said grooves by the abutting face of the next adjacent disk, certain of said disks being provided with a peripheral slot through which type may be removed from and inserted in the grooves of the next adjacent disk.

2. A printing device comprising, a series of concentric type carrying disks arranged in face to face relation, each of said disks having type carrying grooves in one face thereof, type in said grooves, the type in the grooves of one disk being held in said grooves by the abutting face of the next adjacent disk, certain of said disks being provided with a peripheral slot through which type may be removed from and inserted in the grooves of the next adjacent disk, and a spring in each of said slots adapted to bear against the grooved face of the next adjacent disk.

3. A printing device comprising, a series of concentric type carrying disks arranged in face to face relation, each of said disks having type carrying grooves in one face thereof, type in said grooves, the type in the grooves of one disk being held in said grooves by the abutting face of the next adjacent disk, and an additional non-type carrying disk arranged in face to face relation with the grooved face of the last type carrying disk of the series and adapted to hold the type of said disk in said grooves, said additional disk being provided with slits extending radially inwardly from the periphery to form a spring finger lying normally in the plane of said additional disks, but which may be pressed outwardly to form a peripheral slot through which type may be removed from and inserted in the grooves of the last type carrying disk of the series.

4. A printing device comprising a series of concentric type carrying disks arranged in face to face relation, each of said disks having type carrying grooves in one face thereof, type in said grooves, the type in the grooves of one disk being held in said grooves by the abutting face of the next adjacent disk, certain of said disks being provided with a peripheral slot through which type may be removed from and inserted in the grooves of the next adjacent disk, an additional non-type carrying disk arranged in face to face relation with the grooved face of the last type carrying disk of the series and adapted to hold the type of said disk in said grooves, said additional disk being provided with slits extending radially inwardly from the periphery to form a spring finger lying normally in the plane of said additional disks, but which may be pressed outwardly to form a peripheral slot through which type may be removed from and inserted in the grooves of the last type carrying disk of the series.

JOSEPH WEIMONT.
